UNITED STATES PATENT OFFICE

2,487,406

MECHANISM FOR CRUSH DRESSING
GRINDING WHEELS

Merton H. Arms, Springfield, Vt., and Walter J. Augustenovich, Kansas City, Mo., assignors to Bryant Chucking Grinder Company, Springfield, Vt., a corporation of Vermont

Application July 26, 1946, Serial No. 686,408

7 Claims. (Cl. 125—11)

1

This invention relates to the dressing of grinding wheels by crushing.

One object is to provide a dressing mechanism well adapted for use on grinding wheels having portions of substantially different diameters, avoiding the rapid wear of the crushing rolls caused by substantial relative slippage between certain portions of the roll and the wheel where such diameter differences are substantial.

A further object is to provide for positive rotation of at least a portion of the crushing roll which is in contact with the wheel, the wheel being rotated by the rotated crushing roll, or, if desired, positively rotated at a relatively low speed.

Still another object is to provide an improved mounting and drive for the crushing roll with mechanism to move the roll into and out of crushing position.

Further objects and advantages will appear from a description of certain embodiments of the invention shown in the accompanying drawings in which

Figure 1 is a fragmentary plan view of the upper portion of a grinding machine showing mechanism embodying the invention.

Figure 2 is a side elevation of the same mechanism, a portion of the grinding machine frame being shown in section.

Figure 3 is a detail sectional view on line 3—3 of Figure 1.

Figures 4 and 5 are central cross sectional views showing two constructions of crushing rolls either of which may be employed to crush dress a grinding wheel to the same contour.

Referring first to Figure 2, at 1 is shown a portion of the frame of a grinding machine, suitably supporting for rotation a spindle 2 (see Figure 1), to which a grinding wheel 3 is secured. It will be noted that this grinding wheel comprises two grinding surfaces axially separated. One of these, at 4, is a cylindrical surface, and the other, at 5, has a convex periphery. They may be two separate grinding wheels with a spacer between them rather than a single wheel, if desired. The mean diameter of the convex periphery portion 5 is substantially smaller than the diameter of the portion 4.

The frame 1 also has fixed thereto, a plate 6 which is shown as arranged in a horizontal plane. To this plate 6 is secured a bracket 7, the securing means comprising screws 8 passing through a flange 9 of the bracket and entering into threaded holes in the plate 6. The holes through the bracket flange 9 may be larger than the bolts

2

sufficiently to permit a horizontal adjustment of the bracket 7. As shown this adjustment is effected by turning a screw 10 threaded into the bracket 7 and journaled in a bracket 11 extending upwardly of the plate 6.

This bracket 7 has a pair of spaced bearing flanges 15 at its rear end for pivoting between them a support 20, the pivot being at the trunnions 19. This support 20 carries thereon a motor 21, the shaft of this motor being connected through a driving belt 22 with a belt pulley 23 fixed to a shaft 24, journaled in a casing 25 carried by the support 20.

This shaft 24 is connected by a train of gearing, 15 including the gears 26 carried on the shaft 24 and a gear 27 carried on a spindle 28 journaled in a casing 29 carried by the support 20. This spindle 28, in turn, carries the crush dressing roll, indicated generally at 30. The spindle 28 is shown 20 as extended through a disk 31 forming one element of a labyrinth packing which prevents foreign material from gaining access to the bearings supporting the spindle 28.

The support 20 is connected by a link 35 pivoted 25 at one end thereto to a piston rod 36 which enters a suitably hydraulic power cylinder 37 where it is provided with the usual piston (not shown).

In the position of the parts shown in Figure 2, the piston 36 is in its upper position, holding the support 20 in the position to present the crush dressing roll 30 into contact with the grinding wheel 3. By introducing fluid under pressure into the upper end of the cylinder 37 by any suitable means (not shown), this piston may be driven 30 downwardly, rocking the forward end of the support 20 upwardly and removing the crushing roll from contact with the grinding wheel.

It is desirable to have the crusher roll contact the grinding wheel in the line of contact which 40 the wheel makes with the work, and in order that this may be done readily, an adjusting screw 40 extends upwardly from the bracket 7 in position to be contacted by a pad 41 on the casing 25, and thereby determine the lowest position of the 45 crushing roll when it is in position to operate upon the wheel. In the machine shown, which is for internal grinding, the wheel diameters are necessarily rather small, and differences in diameter between different portions have correspondingly greater relative importance than in large diameter wheels in connection with the subject matter of this invention. The feed between the crushing roll and the wheel is 50 accomplished by the usual feed mechanism of the

machine which moves the grinding wheel toward and from the work.

It has been before noted that the mean diameters of the two portions 5 and 4 of the grinding wheel are substantially different, and if it be attempted to crush dress such a wheel with a single crushing roll having crushing portions of complementary diameters to that of the wheel, slippage must take place between some portion of the wheel and the crushing roll, and such slippage is effective in producing a grinding action of the grinding wheel on the roll which seriously shortens its life.

In Figures 4 and 5 constructions of crushing roll are shown for preventing such excessive wear. In the form shown in Figure 4, the crushing roll is a multipart roll, comprising a body 50 having a central bore 51 shaped to engage the outer end of the spindle 28, which in this instance is shown as tapered and of such an angle that the body portion 50 may be held tightly for rotation by rotation of the spindle 28. This body portion 50 has a crush dressing periphery 55 for a portion only of its axial length. At another portion of its axial length, the body is of reduced diameter to form a journal portion 56 coaxial with the crushing surface 55 and coaxial with the bore 51. Journalized on this portion 56 is a ring 58, and in order to hold this ring 58 in journaled position, a retaining ring 59 which overlaps a portion of the ring 58 is secured to the body 50 as by screws 60. It will be noted that the outer face of the ring 58 is of substantially different diameter than the outer crushing periphery 55 of the body, and as shown it is larger than that of the body. This outer face or periphery 61 of the ring 58 forms the remainder of the crushing contour of the crushing roll. As shown it is provided with a concavity intended to mate the convexity of the grinding portion 5 of the wheel 3, and of such a diameter that this crushing surface of the ring 58 engages the grinding wheel at the same time that the crushing face 55 engages the portion 4 of the grinding wheel when the grinding wheel is of the size desired.

It will be noted that the crushing roll body is rotated with the spindle 28, and when its surface 55 is brought into engagement with the surface of the portion 4 of the grinding wheel while neither is rotating and the two are thereafter revolved together, the portion 4 of the face of the grinding wheel will be crush dressed, the grinding wheel being driven by friction contact with the crushing face 55. This will also tend to drive the ring 58, but as this ring is free to rotate on the body 50, it will be driven, in turn, by its engagement with the rotating wheel portion 5, pressing thereagainst, and at a different rate of angular velocity than that of the body 50 by reason of the different effective diameters of the engaging parts on the crushing roll and the grinding wheel. As shown, for example, the effective rate of peripheral velocity of the grinding wheel portion 5 is less than the peripheral rate of the grinding wheel portion 4, since it is of smaller diameter. Consequently, the frictional drive rate imparted to the ring 58 by its engagement with the grinding wheel will be slower not only because of the slower peripheral effective speed of the grinding wheel portion 5, but also because of the larger diameter of the effective periphery of the ring 58. Thus each of these parts may be driven at a speed best suited to its engagement with the other part, minimizing the drag between the wheel and the roll, and thus

minimizing the wear on the roll due to the cutting action of the wheel thereon.

In some cases, as when first dressing a new wheel, the ring 58 may be the only portion of the crushing roll which is effective on the grinding wheel, and where such is the case, with the construction shown, the grinding wheel would not be rotated by the body 50 because its surface 55 would not be in engagement with the grinding wheel. In this case, in order to cause rotation of the grinding wheel, the ring 58 is temporarily secured to the body 50 so as to be driven thereby thus to impart the necessary rotation to the grinding wheel for the crush dressing. The means for so doing, as shown at Figure 4, comprises a set screw 65 threaded through a bore 66 in the body 50 and provided with an inner end 67 which may be moved into a socket 68 in the ring 58. A friction plug 70 seated in a socket 71 in the body 50 and pressed into engagement with the set screw 65, as by a spring 72 in this socket, holds the set screw 65 in adjusted position, either into driving engagement with the ring 58 or freeing the ring 58 for rotation relative to the body.

In Figure 5 another form of crushing roll is illustrated for operation on a grinding wheel of the same contour as that operated upon by the crushing roll of Figure 4. This construction comprises a body 50a which has a large diameter portion 51a having a crush dressing periphery identical with that of the ring 58 of Figure 4. It also has a reduced diameter portion 56a on which is journaled a ring 58a having a periphery 55a the same as the periphery 55 of the body 50 in the construction of Figure 4. The portions of the crush surface on the journaled ring and on the body in this construction are thus reversed from that of the construction of Figure 4. The ring 58a is held on the journal portion 56a as by a clamping ring 59a partly overlapping the ring 58a and held in position by screws 60a. With this arrangement of crushing roll, the grinding wheel is driven by its frictional engagement with the portion 51a and the grinding wheel, in turn, drives the ring 55a at a higher rate of speed than is the body 50a. Here, again, if the ring portion is to accomplish the dressing action while the body portion is idle, the ring will be clamped to the body portion so that the ring will be driven thereby. Means for doing this comprises the locking disc 80 which has a laterally extending externally threaded flange 81 meshing with an internally threaded portion 82 of the body 50a, this disk having an annular shoulder 83 adjacent its periphery which may engage against the end face of the ring 58a so that when the disk is tightened it will clamp the ring 58a against the body 50a.

While as shown the crushing roll is power driven and intended to be used when the wheel is free to be rotated by friction therefrom, the power could be applied to the grinding wheel, but this would be at a much slower rate of speed than the grinding speed. It would then be possible to mount all the different diameter portions of the crusher roll for free independent rotation, though, if desired, one might be power driven if at a speed correctly related to that of the corresponding portion of the grinding wheel for the crushing action.

From the foregoing description of certain embodiments of this invention, it will be evident to those skilled in the art that various further modifications and changes might be made without de-

parting from the spirit or scope of this invention.

We claim:

1. In combination, a rotary shaft, means for rotating said shaft, a multi-part crushing roll carried by said shaft, one part of said roll being supported for rotation with said shaft, another part of said roll being mounted coaxially with said first part for rotation relative to said first part, each of said parts having grinding wheel crushing peripheries, the crushing peripheries of said one and said other part being of substantially different effective diameters.

2. In combination, a rotary shaft, means for rotating said shaft, a multi-part crushing roll carried by said shaft, one part of said roll being supported for rotation with said shaft, another part of said roll being mounted coaxially with said first part for rotation relative to said first part, each of said parts having grinding wheel crushing peripheries, the crushing peripheries of said one and said other part being of substantially different effective diameters, and means for locking said parts against relative rotation.

3. A crushing roll presenting a peripheral wheel crushing portion and a journal portion coaxial with said wheel crushing portion, and a ring journaled on said journal portion and having a wheel crushing periphery of substantially different effective diameter than the effective diameter of said crushing portion.

4. A crushing roll presenting a peripheral wheel crushing portion and a journal portion coaxial with said wheel crushing portion, a ring journaled on said journal portion and having a wheel crushing periphery of substantially different effective diameter than the effective diameter of said crushing portion, and means for releasably securing said ring to said roll against relative rotation.

5. A crush dressing roll comprising a body having a bore to receive a rotating spindle and having at a portion of its axial length a wheel crushing periphery coaxial with said bore, and another portion of its axial length formed as a journal

part, a ring journaled on said journal part and having at its periphery a wheel crushing portion, and a retaining ring secured to said body and overlapping said journaled ring for retaining said journaled ring on said journal portion.

6. A crush dressing roll comprising a body having a bore to receive a rotating spindle and having at a portion of its axial length a wheel crushing periphery coaxial with said bore, and another portion of its axial length formed as a journal part, a ring journaled on said journal part and having at its periphery a wheel crushing portion, a retaining ring secured to said body and overlapping said journaled ring for retaining said journaled ring on said journal portion, and an element carried by said body and adjustable to engage or to free said journaled ring for releasably securing said journaled ring against rotation relative to said body.

7. A crush dressing roll having dressing peripheries of different effective diameters arranged adjacent to each other for simultaneous dressing action, said peripheries being on separate portions of said roll free for independent coaxial rotation at different angular velocities.
